UNITED STATES PATENT OFFICE.

THOMAS MIDGLEY, SR., AND THOMAS MIDGLEY, JR., OF WORTHINGTON, OHIO.

METHOD OF CONSTRUCTING COLLAPSIBLE CORES.

1,157,118.

Specification of Letters Patent. Patented Oct. 19, 1915.

Application filed July 16, 1914. Serial No. 851,270.

To all whom it may concern:

Be it known that we, THOMAS MIDGLEY, Sr., and THOMAS MIDGLEY, Jr., citizens of the United States, residing at Worthington, in the county of Franklin and State of Ohio, have invented certain new and useful Improvements in Methods of Constructing Collapsible Cores, of which the following is a specification.

10 Our invention relates to the art of manufacturing tire casings forming the wear resisting portions of pneumatic tires and pertains more specifically to a method of constructing collapsible cores used in the manufacture of these casings.

15 Collapsible cores themselves are used particularly where inextensible edged casings are made, since it is necessary that the iron core about which these casings are formed, should be removed. Should the cores themselves be solid, it would be impossible to remove the inextensible edged casings therefrom without breaking either the core or the casing. Therefore, it is essential that the 20 finished core be made up of a plurality of segments readily collapsible from the annular form which they must of necessity assume when in true assembled position.

25 In constructing these cores in accordance with our invention, an important step resides in assembling a plurality of ring sections to form a complete ring, placing this assembled ring in a mold, and casting a core onto said sections.

30 In order to avoid casting the core proper in one piece and subsequently cutting it up into the desired number of sections, we place division members in the mold to divide the imprint up into the desired number of sections and then cast the core by permitting the metal to flow onto the various sections.

35 The step just outlined, as well as the step outlined in the foregoing paragraph, form two very important features of our invention, and they may be joined to great advantage in producing these cores, but we do not deem them inseparable and consequently our invention contemplates the use of one of these steps to the exclusion of the other, 40 or both together as may be desired and as will be apparent from the appended claims.

45 It has been common practice to cast a core in one piece, properly finish it, cut it up into the various segments as desired, and then 50 suitably face the segments ends. When it was desired to again assemble the same,

clamping means of some type, usually rings, have been resorted to. This is an expensive and laborious procedure and the steps of our invention, as above outlined, aim to provide 55 a collapsible core in much less time and at considerable less expense.

A further important step of our invention resides in forming the division members of complementary and coöperating plates, placing these plates in superimposed relation with each other in the mold to divide the imprint up into the desired number of segments and subsequently forming 60 a connection between these division plates and the segments by permitting the metal to flow onto the various plates during the casting operation, whereby the segments are initially cast to form a complete ring and are suitably faced by the same act.

65 Other important steps of our invention reside in so forming the division plates that they will positively bond themselves to the adjacent ends of the core segments and also in the peculiar manner in which the plates forming the division members are attached to each other as a whole and to each other 70 in two groups and in subsequently finishing the same, all as will be more apparent hereinafter.

75 The various novel features of our invention will be more clearly seen after a further detailed description of the accompanying sheets of drawings, wherein portions of a collapsible core are shown and wherein similar characters of reference designate corresponding parts.

In these drawings; Figure 1 shows approximately half of an iron core constructed by using all the steps of our method. Fig. 2 is a central vertical section through one of the division members used by us and showing the iron core segments in dotted outline and in true relation therewith, Fig. 3 is a section taken on line 3—3 of Fig. 2 through the division member only, Fig. 4 is a face view of a division member showing a suitable sand core baked thereon, Fig. 5 is a transverse section of the structure shown in Fig. 4, and, Figs. 6, 7 and 8 are sectional views taken on lines 6—6, 7—7 and 8—8 respectively of Fig. 1.

In our co-pending application, Serial Number 851269, filed July 16, 1914, we have specifically described a core wherein the division members and sectional ring have been used. In Fig. 1, we have shown the upper

half of a collapsible iron core, the segments shown being denoted 1, 2 and 3. These segments are all cast hollow and each is provided with an opening 4 through which the core sand may be withdrawn. Rigidly attached and cast in connection with these segments, are ring sections 5, 6 and 7, the sections 5 and 7 being preferably identical in structure and two sections 6 being provided to form the completed ring. These rings are all detachably connected together as at 8 by a coöperating tongue and groove construction on the meeting ends of the various sections and are held together by removable pins or bolts.

In carrying out our method we assemble the various ring sections to form a complete ring and then bake a sand core thereon, this sand core being shown at 9 in Figs. 6, 7 and 20 8. It will be noted that this sand core 9 covers the major portion of the complete ring itself, but leaves exposed its outer flange projection. The combined ring and sand core is then placed in a mold, allowing the 25 uncovered portion of the ring to project into the imprint of the previously drawn pattern. The iron core itself is then cast whereupon the metal flows about the flange projection of the ring and in this manner attaches 30 itself. We preferably provide a peculiar shape of flange projection to insure this attachment in the event that, when the metal is poured, it may not be sufficiently hot to bond itself thereto by fusion, although the 35 projecting flange may itself be prepared by acid or a sand blast, so that a clean free surface is obtained from which all oxid scale or other foreign matter is removed to assist somewhat in causing the metal to fuse itself 40 thereon. The peculiar shape of this flange between points where the ring sections are connected together, except at the openings 4, is shown in Fig. 6 from which it will be apparent that a rigid connection must be established.

Face plates are usually necessary for the abutting ends of the various core segments, in order to avoid chipping or breaking away of the edge portions. If it is then desired 50 to cast the various segments independent of each other, or in positive engagement with their respective face plates, this may be done in the following manner: A plurality of plates, such as shown in Figs. 4 and 5 are 55 provided. Each division member as we have illustrated in the present instance, is formed of four plates as is shown in Figs. 1 and 2, or two to form the facing for each end of each segment as is shown in Fig. 5. In this 60 figure, the plates 10 and 11 are provided, the plate 10 having a plain face, while the plate 11 is apertured and bulged outwardly as is shown at 12. These bulged out portions are confined to that portion of the 65 plate which is within the normal area of the

iron core, which is shown in Fig. 4. These two plates are also spot welded or otherwise rigidly connected together, as is shown at 13, at a number of points within the area covered by the iron core. A second set of 70 plates similar to those just described, and designated 14 and 15 as shown in Figs. 2 and 5, are also provided, these plates being so shaped that they comfortably nest with the plates 10 and 11, but the bulged-out portions 16, similar to those formed at 12, are made to extend in the opposite direction. These two latter plates are also rigidly attached to each other within the area normally covered by the iron core and the two 75 sets of plates then nested and if desired, a coating of graphite 19 is placed between the two sets or some other means may be resorted to for preventing the two sets of plates from fusing together because of the 80 generated heat in casting should this heat be of sufficient intensity. These two sets of plates, now comfortably nested are all rigidly connected together, as is shown at 17, this connection being preferably made by 85 spot welding or riveting and being entirely without the normal area covered by the iron core. These nested plates forming one division member then have a suitable sand core baked thereon, this sand core being shown 90 at 18 in Figs. 4 and 5, the inner outline of which conforms to the outside shape of the completed iron core. The required number of division members are then placed in the 95 mold to divide the imprint tip into the desired number of segments and if it is desired to use the detachable ring sections, these division members are placed in the imprint at points adjacent the points of jointure of the various ring sections. The metal is then 100 permitted to flow into the various segments forming the imprint and will enter the apertured portions 12 and 16 to form a rivet head after cooling. Because of the welded 105 connections 13 between the two plates 10 and 11 and the plates 14 and 15, each end of the various segments will have rigidly attached thereto a plain faced facing, it being understood that the apertured portions 12 and 16 are provided should the metal be poured 110 sufficiently cool that it will not fuse itself to the metal of the facing members. It will, of course, be apparent that the main pattern must be provided with suitable core prints to accommodate the various inlaid metal 115 parts carrying their sand cores. When the casting is taken from the sand, that portion of the plates forming each division member that projects above the casting, is chipped off flush with the casting, taking away with 120 it the riveting 17 that held the four plates 10, 11, 14 and 15 together, the riveting 17 being preferably provided to avoid distortion 125 of the plates due to heat, etc., during 130 casting.

If the ring sections have been used in connection with the division member, the pins at each joint that held the various ring sections together, are withdrawn, the holes are 5 reamed and a hardened steel pin again inserted. The iron core is now completely formed, with the exception of it being machined to proper size and when this has been done, it is ready for use in the manufacture 10 of tire casings.

By the employment of either a portion or all of the steps as outlined above, an efficient collapsible core may be produced at a very small expense when considered with the expense of making as is at present in use. 15

What we claim, is:

1. The method of constructing collapsible cores which consists in assembling a plurality of ring sections to form a complete 20 ring, placing said assembled sections in a mold, and casting a core onto said sections.

2. The method of constructing collapsible cores which consists in assembling a plurality of ring sections to form a complete ring, 25 placing said assembled sections in a mold, placing a set of division members in said mold in definite relation with said ring sections to cause the core to be formed in sections, and casting a corresponding set of 30 core segments onto said sections.

3. The method of constructing collapsible cores which consists in detachably connecting together a plurality of ring sections to form a complete ring, placing said assembled sections in a mold, placing a set of separable division members in said mold adjacent the points of jointure of said ring sections, and casting a corresponding set of core segments onto said sections and onto 40 said members.

4. The method of constructing collapsible cores which consists in detachably connecting together a plurality of ring sections to form a complete ring, baking a suitable 45 sand core onto said assembled sections leaving the outer edge portions free, placing said assembled ring and said core in a mold, placing a set of separable division members in said mold adjacent the points of jointure 50 of said ring sections and casting a corresponding set of core segments onto said sections and onto said members.

5. The method of constructing collapsible cores which consists in assembling a plurality 55 of ring sections to form a complete ring, baking a suitable sand core onto said sections leaving the outer edge portions free, placing said assembled ring and sand core in a mold, and casting a core onto said sections. 60

6. The method of constructing collapsible cores which consists in constructing a set of division members so that each member is formed of a plurality of plates, baking a 65 suitable sand core around said division

members, placing said division members and their sand cores in a mold to divide the imprint up into the desired sections, and then casting by permitting the metal to flow into the various portions of the imprint. 70

7. The method of constructing collapsible cores which consists in constructing a set of division members so that each member is formed of a plurality of plates, facing said division members in a mold to divide the 75 imprint into the desired sections, and then casting by permitting the metal to flow into the various portions of the imprint.

8. The method of constructing collapsible cores which consists in dividing up an imprint of an annular core into the desired 80 number of sections by the placement in the mold of a set of division members, each member being formed of a plurality of separable plates so formed that the metal from one section can not flow to another section during the casting operation to form the core itself into a plurality of sections. 85

9. The method of constructing collapsible cores which consists in dividing up an imprint of an annular core into the desired 90 number of sections by the placement in the mold of a set of division members, and providing each member with oppositely disposed self attaching structures before they 95 are placed in the mold, each member being formed of a plurality of separable plates so formed that the metal from one section cannot flow to another section during the casting operation to form the core itself into a plurality of sections rigidly carrying face 100 plates on the section ends.

10. The method of constructing collapsible cores which consists in providing coöperating plates to serve as division members, 105 providing one surface of each plate forming the division member with a self attaching formation, superimposing the plates forming each division member leaving the attaching formations on the outside and placing 110 said division members in a mold to divide the imprint up into the desired sections, and casting the core by permitting the metal to flow into the various portions of the imprint to attach itself to the plates of said division 115 members.

11. The method of constructing collapsible cores which consists in forming division members by rigidly connecting together a group of plates within the normal area of an 120 iron core and rigidly connecting two groups together outside of the normal area of the iron core to form a set, providing the outside plates of each set with self attaching formations, placing said sets in a mold to divide 125 the imprint into sections, casting the various sections onto the division members, and removing that portion of each set of plates outside the normal area of the iron core after it is cast. 130

12. The method of constructing collapsible cores which consists in forming division members by superimposing two plate elements to form each member, connecting the plate elements of each member together outside the normal area of an iron core, placing said members in a mold to divide the imprint into sections, casting the various sections onto the outside faces of said members, and removing that portion of each member outside the normal area of the iron core after it is cast.

13. The method of constructing collapsible cores which consists in forming division members by rigidly connecting together a group of plates within the normal area of an iron core and rigidly connecting two groups together outside of the normal area of the iron core to form a set, providing the outside plates of each set with self attaching formations, baking a suitable sand core onto said sets outside the normal area of an iron core, placing said sets in a mold to divide the imprint into sections, casting the various sections onto the division members and onto the exposed portions of said ring sections, and removing that portion of each set of plates outside the normal area of the iron core after it is cast.

14. The method of constructing collapsi-

ble cores which consists in assembling a plurality of ring sections to form a complete ring, baking a suitable sand core onto said sections leaving the outer edge portions free, placing said assembled ring and sand core in a mold, forming division members by rigidly connecting together a group of plates within the normal area of an iron core and rigidly connecting the two groups together outside of the normal area of the iron core to form a set, providing the outside plates of each set with self attaching formations, baking a suitable sand core onto said sets outside the normal area of an iron core, placing said sets in the mold adjacent the points of jointure of said ring sections to divide the imprint into sections, casting the various sections onto the division members and onto the exposed portions of said ring sections, and removing that portion of each set of plates outside the normal area of the iron core after it is cast.

In testimony whereof we affix our signatures in presence of two witnesses.
